CLOSED ROTATABLE SWITCH

Erwin J. Saxl, Harvard, Mass.

Application April 19, 1950, Serial No. 156,788

27 Claims. (Cl. 200--32)

1

This invention relates broadly to a device for making and breaking an electric circuit, and has for its principal objects to provide a device that will positively make a circuit and substantially instantaneously break it so as to operate current impulses in the circuit, the duration of which will be independent of the non-maximum speed at which the device is actuated; which will require very little energy to operate; which will have a minimum of parts subject to wear and such mechanical limitations as to fatigue, inertia, etc.; which will be inexpensive to manufacture; and which may be used to control and/or actuate circuits requiring large power consumption from input signals having low power level.

In its broadest aspect the device is in the form of a light, closed receptacle, container, envelope or capsule, rotation of which may be effected with a minimum of power interposed in an electric circuit of relatively high potential and operable by a small power input positively to make the circuit and immediately thereafter automatically to break it so as to generate a substantially instantaneous impulse in the circuit of normal support intensity. While the term "capsule" is herein used in a generic sense, I shall for brevity usually refer to the device as a receptacle, using that term generically.

As illustrated, the closed receptacle is rotatable, has a small free body of conductive material therein adapted to be raised a comparatively small distance from an initially stable position at the bottom of the receptacle to an elevated position of instability from which it gravitates suddenly, returning back to the bottom of the receptacle, and spaced terminals situated in the path of the return movement of the said gravitating free body, momentarily to make contact with the moving body prior to arrival thereof at its stable position, and hence to create an impulse in the circuit.

In certain of its several forms the receptacle includes one or more cups, depressions or scoops adapted to receive the free body and to raise it to a predetermined level and then to allow it to gravitate to its original level, the spaced terminals being arranged therein in such positions as to be momentarily connected to each other through the said free body as it moves relative thereto from its elevated position to its original level. Preferably the receptacle should be evacuated, sealed and filled with an inert gas or reducing atmosphere to avoid oxidation.

It is contemplated that the receptacle may be employed in a circuit containing a comparatively

high-power consuming device such as a counter, computer, measuring device or signal, and the impulse generated in the circuit by rotation of the said receptacle, while requiring little power to produce, will be of sufficient intensity to operate such instrumentalities. As thus used the receptacle may be connected for rotation to a watt-hour meter, for example, and the amount of current passing through the meter will be recorded by the counter without adversely affecting the accuracy of the meter.

The invention will now be described in greater detail with reference to the accompanying drawings wherein:

15 Fig. 1 shows a transverse section of one form of the device interposed in an electric circuit which has in it a conventional type of counter, the device being of cylindrical form and the section being taken on the line 1—1 of Fig. 2;

20 Fig. 2 is a vertical section of the device taken on the line 2—2 of Fig. 1 and shows the mounting for the receptacle;

25 Fig. 3 is a vertical diametrical section through a preferred form of the receptacle wherein the receptacle is materially simpler and cheaper to make than that shown in Figs. 1 and 2;

Fig. 4 is a section on the line 4—4 of Fig. 3;

30 Fig. 5 is a vertical section of an alternative form of the receptacle; Fig. 5a is a vertical section on the line 5a—5a of Fig. 5.

Fig. 6 is a fragmentary vertical section through a receptacle designed especially for receiving a rigid ball for making and breaking the circuit;

35 Fig. 7 is a modified form of the receptacle shown in Fig. 6 showing a receptacle of non-conductive material through the wall of which pass a pair of closely spaced terminals;

Fig. 8 is a vertical section through a receptacle designed to provide a plurality of impulses so as, 40 for example, to actuate several circuits for each rotation;

Figs. 9 and 9a show in cross section a form of the invention wherein the receptacle is oscillated;

45 Fig. 10 shows in longitudinal cross section another form of the receptacle and its supporting and rotating parts;

Figs. 11, 12 and 13 show in vertical section forms of the receptacle having the terminal electrodes entering at the axis of rotation of the receptacle but differently terminating therein;

Fig. 11a is a side elevation of the receptacle shown in Figs. 11, 12 and 13;

50 Figs. 14 and 15 show in side elevation two positions of the receptacle which herein is of elong-

gated tubular form and having its ends slightly oppositely curved;

Fig. 14a is a cross section of the receptacle shown in Figs. 14 and 15;

Fig. 16 shows in plan view a duplex form of the receptacle that is shown in Figs. 14 and 15;

Fig. 17 shows in longitudinal section an important variation of those forms of receptacle that are shown in Figs. 11, 12 and 13;

Fig. 18 shows, in side elevation and partly in longitudinal section, the circuit making and breaking device used in connection with an electric-light bulb to cause a constant series of sufficiently short flashes for any desired purpose;

Figs. 19 and 20 show in cross section and in plan one form of the circuit making and breaking device used in connection with a watt-hour meter;

Figs. 20a and 20b are sectional details, parts being broken away, of alternative constructions of the electrode supports and associated bearings or bushings; and

Fig. 21 shows in cross section one of the many possible adaptations of my invention, it being here shown in a light buoy to cause flashing thereof.

The device has for its primary purpose the generating of a plurality of strong impulses in an electric circuit of standard voltage by providing means for making and breaking such a circuit which may be actuated by weak actuating means such as a small electric clock mechanism or by means which would be made inaccurate if much power output was imposed upon it.

Referring first to Figs. 1 and 2, there is shown by way of example the device in the form of a closed receptacle 10 interposed in a circuit 12 having in it a counter 14. The circuit is connected by leads 16 to a 110-volt power source or any other conventional and readily available source of electric power, whether it be direct current or alternating current. The illustrated form of the receptacle shown in Fig. 2 is particularly intended for laboratory use and hence is not as light in weight or as economical to construct as the forms of the receptacle shown in most of the other figures. However, it illustrates the principle involved and accordingly will now be described to portray the principal idea of the invention.

The receptacle comprises essentially two cup-shaped members 20 and 22 circular in cross section and telescopically engaged one within the other, the external surface of the member 20 carrying threads for engagement with corresponding threads formed on the inner surface of the member 22. The circular end wall of the member 22 has a central opening 26 therein which is of substantially the same diameter as the inside diameter of the cup 20, so as to form an annular lip 28 which serves to hold a glass plate 30 between it and the lip of the cup 20 in a rigid fashion and hence enable observation of the inside of the receptacle during rotation thereof. A shaft 32 is fixed in the end wall of the cup 20 and is journaled in a bearing 34 formed in a metal plate 36, the latter being riveted, bolted or otherwise fastened to an insulating supporting member 37. A shaft 38 is heat sealed into the glass plate 30 in axial alignment with the shaft 32, and is journaled in a bearing 40 formed or otherwise inserted in a metal plate 42. As thus constructed, the receptacle may be rotated about the horizontal axis of the shafts 32 and 38, and to effect such rotation

there is fastened to the shaft 38 a gear 44, this being driven by a worm 46 which may be connected to any source of power, as, for example, the take-off at a watt-hour meter or other current measuring instrument from a small, comparatively weak electric clock, or a weak electronic circuit, the current from which is not of sufficient strength to actuate a mechanical device such as a computer, counter, integrator, or other similar measuring instrument whether mechanically operated or electrically operated.

Within the receptacle, in the inner peripheral wall of the cup 20, there are formed one or more depressions, cavities or scoops 48 within which may be placed a body or globule of mercury 50, although it is to be understood that any other conductive metallic material which will be liquid at normal temperatures or any non-vaporizing conducting liquid which will not be disassociated by current passage or even a rigid metal ball may be used. Also within the receptacle there is fixed to the inner end of the shaft 38 a balanced terminal member 52 in the form of a two bladed paddle, the extremities 53 of which terminate close to the inner peripheral surface of the cup 20 and are so shaped that, for example as shown in Fig. 1, the terminal end of each blade is situated laterally to one side of the cavity or depression 48. In operation, the receptacle is caused to rotate in the direction of the arrow so that the cavity moves in a direction always to precede the blade of the paddle closest to it. As the receptacle rotates the body of mercury or other conductive material is carried in a clockwise direction, Fig. 1, from its initially stable position at the level of the bottom of the receptacle upwardly through an angle of substantially 45°, although this will vary depending upon the depth of the cavity and the exact shape thereof, whereupon it will suddenly spill out of the cavity and run downwardly along the inner curved surface of the receptacle toward the bottom, where it will eventually settle and remain in a stable position until it is again received in a depression 48 and carried upwardly, this of course depending upon the speed at which the receptacle is rotated. If the blade 52 is fixed as heretofore described and travels with the receptacle immediately upon spilling of the mercury from the cavity, it will pass beneath the terminal end 53 of the blade adjacent to the cavity as it descends along the surface of the receptacle, thus making a momentary contact between the blade and the receptacle. The inner wall of the receptacle, at least, is composed, in this form of the invention, of a conductive material, and accordingly the momentary passage of the mercury between the edge of the blade and the inner surface of the receptacle will establish an electric contact so that there will be a momentary closing of the circuit 12, followed immediately by a breaking of the circuit so that for an instant there is an impulse in the circuit corresponding to the voltage impressed thereon. The making-and-breaking of the circuit will be positive, and the breaking will be clean since the mercury will flow quickly to the bottom of the receptacle and hence the duration of the contact will be entirely independent of the rate of rotation of the receptacle, so that regardless of whether the receptacle is turning at an almost indiscernible speed or at a high rate of speed, the contact will be made and broken under the same condition so that the impulse generated in the circuit 12 will always be identical in dura-

tion. Since there are two depressions there will be two impulses for each revolution of the receptacle. However, it is within the scope of the invention to have one or a plurality of depressions depending upon the use. Binding posts 52 and 54 provide for connecting the device in the circuit.

Instead of using one single pair of paddles only, a multiple number of contactors may be used. This makes it possible to actuate the contacting and decontacting mechanism for smaller angles of deflection than the 180° necessitated by the device described previously.

While, as described, the paddle 52 is fixed to the shaft 38, it is perfectly possible to mount the paddle on the shaft 38 so that it is free to turn thereon and then to counterweight it so that it will remain substantially in the position shown in Fig. 1 during the rotation of the receptacle, and this is within the scope of my invention. With such construction the mercury would flow back after being spilled from the recess and, due to its momentum, over-run the lowermost point, make contact with the blade 52 and then return to the bottom. The paddle would in such case be of sufficient mass or would be counterweighted sufficiently to be substantially unaffected by the impact of the mercury.

Much simpler and cheaper forms of the receptacle which are admirably suited for use where the power for rotating the same is very small and weak are shown in Figs. 3, 4 and 5. Referring to Fig. 3, the receptacle 10a is shown as composed of a glass base in the form of a flat plate 56 into one surface of which is sealed the peripheral edge of a metal cup or thimble 58. The receptacle as thus constructed is mounted for rotation on a pair of axially aligned shafts 60 and 64, the former being heat-sealed into the glass plate 56, and the latter being welded, riveted or otherwise secured to the wall of the thimble 58. The inner end of the shaft 60 has fastened to it a terminal 62 which is in the form of a double-bladed paddle of substantially the same shape as shown in Fig. 1. The metal receptacle has a pair of spaced, diametrically arranged recesses or cavities pressed thereto and a body of mercury 69 is placed in the receptacle. Rotation of the receptacle in the direction of the arrow, in Fig. 4 for example, by means of a gear and worm such as shown in Fig. 2, will produce the same action as described hereinbefore; that is, the body of mercury will be lifted from an initially stable position at the bottom of the receptacle to an elevated position where it will spill from the recess and flow downwardly to the bottom of the receptacle. During such return flow to its initial stable position, it will pass between the edge of the blade 62 and the wall of the receptacle and, since the wall is metal, will establish a momentary complete circuit so as to produce an instantaneous impulse.

An alternative form of a cheap, easily manufactured receptacle is shown in Figs. 5 and 5a at 10b as comprising a pair of substantially flat, circular, glass plates 70 joined in parallel spaced relation by an annular metal wall 74 to provide a hollow receptacle within which are fixed, as by spot welding to the annular wall, a pair of nearly diametrically arranged guide plates 72. Each plate 72 has a cup or scoop 71 at its outer end which receives the body of mercury in the receptacle and a generally radially inwardly extending wall 73, one on one side of and the other on the other side of a pair of axially aligned

shafts 78 and 80, each sealed in the plates 70 so that their inner ends are closely adjacent. The terminal ends 75 at opposite sides of the shafts 78 and 80 are substantially concentric therewith and close enough thereto so that as the body of mercury runs inwardly along the wall 73 it will collect for an instant in the ends 75 and bridge the gap between the shafts 78 and 80, thereby making the circuit. With this construction the mercury will alternately run in along one guide wall, make the contact and then drop to the cup or scoop 71 of the other guide, whereupon the process will be repeated in the next half revolution of the receptacle. By omitting one scoop, this device is made operative for a single contacting-and-decontacting impulse per revolution, giving, without gearing, one count per revolution.

In the foregoing examples or embodiments of my invention, the contact-making body is referred to as mercury or some other liquid of suitable kind. However, a solid ball of metal or other conductive material may be employed, for example, as shown in the modified forms of the receptacle illustrated in Figs. 6 and 7. In Fig. 6 there is shown a rigid cylindrical receptacle, the inner curved wall of which has a depression or recess 84 therein in which may be seated a metal ball 86 in the operation of the device. In the wall of the receptacle there is inserted an insulator 88 in the form of a glass bead or piece through which there passes from the outside of the receptacle to the inside a terminal wire 90 having as its inner end a bentover terminal 92 which is insulated from the wall of the receptacle by a narrow air gap 94. The outer end of the terminal wire 90 is connected to a metal ring 96 surrounding the receptacle but insulated therefrom by a ring of insulation 98. A brush may be held in contact with the metal ring 96 so as to establish a slip take-off between the rotating receptacle and the circuit to be established. When the receptacle rotates in the direction of the arrow, on Figs. 6 and 7, the ball 86 will be carried up to substantially the position shown in Fig. 6, whereupon it will spill out of the cavity 84 and roll down, as shown in dotted lines in the several positions illustrated, passing over the terminal 92. For a brief instant it will make contact with both the wall of the receptacle and the terminal 92 at the air gap 94 so as to establish a complete circuit, and then will pass out of contact to the bottom of the receptacle. Since there is very little friction in the receptacle, the ball 86 will tend to oscillate before it settles to a stable position and might return far enough to make a second contact and hence produce an error in the circuit by putting in a false impulse. Accordingly, there may be a stop in the form of an inclined ramp 100 adjacent to the terminal 92 and at a side opposite the direction of movement of the receptacle, so that as the ball rolls by the terminal, it passes over it to the bottom of the receptacle, and then, if the ball has reached another release point, it returns toward the terminal 92, and will contact with the stop which will prevent it again reaching the terminal 92 until the receptacle has made a complete half revolution.

In Fig. 6, the receptacle wall is composed of metal or has an inner surface of metal. However, as shown in Fig. 7, the receptacle wall may be made of an insulator, for example, glass 101, and there may be inserted in one part thereof a pair of closely spaced terminal wires 102 and 104, the ends of which terminate on closely spaced plates

with an air gap 105 therebetween so that when the ball 86 rolls along the inner surface it will make contact with the plates at the air gap 105 and thus establish a momentary circuit.

The receptacle, envelope or capsule in the various forms (Figs. 1 to 7) makes one or two contacts, and hence one or two impulses for each revolution. However, in some cases it may be desirable to have a plurality of impulses created for each revolution, creating a plurality of impulses in the same or different circuits. Accordingly, a device as shown in Fig. 8 may be made which consists of a pair of shallow disk-shaped members 106, 108, joined by peripheral flanges 110 and having in their walls a plurality of sealed-in glass beads 112, each of which serves to support a terminal 114 in one wall opposite a terminal 116 in the opposite wall. The terminals 114, 116 may be connected by conventional conductors which are led to slip rings 118 on co-axial shafts 120, 122, so that rotation of the receptacle, envelope or capsule may be produced about a common axis. A body of mercury 124 is included in the seated receptacle and upon rotation will be carried from an initially stable position at the bottom of the receptacle to an elevated position, where it will fall downwardly between successive terminals 114, 116, making contact with each pair of such terminals as it passes therebetween to produce an impulse in the circuit or circuits in which the receptacle is interposed. The receptacle in each of the foregoing examples should be evacuated and filled with an inert or reducing gas such as argon, nitrogen, helium, etc. to avoid oxidation of the metal electrodes by the action of the hot spark.

Figs. 9 and 9a show other embodiments of my invention comprising means for providing instantaneous conducting. Therein a drop of mercury 148 lies at the bottom of the rotatable receptacle or envelope 141. Such receptacle or envelope may be mechanically, electrically or otherwise linked to a moving mechanism, such as a mechanical pendulum.

By a pendulous oscillation of the receptacle or envelope 141, 141a, such as shown in Figs. 9 and 9a, the electrode 142 will then temporarily pass through the pool of mercury, and thereby establish contact between the single electrode 142 and the conductive envelope 141, shown in Fig. 9. From the single electrode actuation it is possible thereby to operate servo-mechanisms, such as electrically operated clocks that are actuated to follow the initial impulses of the master pendulum with mercury actuator connected thereto.

In Fig. 9a the same idea is presented with the exception that instead of a single electrode 142 having in operation a pendulous contacting motion, as shown in Fig. 9, there are shown in Fig. 9a two electrodes 143, 144. However, it is possible to provide quite a number of electrodes in this manner within the limits of physical spacing. Therefore two is not the limiting number of electrodes, but they are shown as indicative of a multiplicity of electrodes that can be applied in the same receptacle or envelope. Thereby a multiplicity of circuits can be operated from the pendulous mechanism instead of the single contact shown in Fig. 9.

In this manner electromechanical means for timing devices and multiple as well as singly actuated contacting mechanism can be established, such as required in certain types of sweep circuit, cathode ray followers, trigger circuits, pulsing circuits and other equipment depending thus far

upon electronic means only. While electronic components for the purposes mentioned have their just and proper field where their extremely high speed is an asset, the mercury actuator shown has the advantage for slower operating speeds. Also it is inexpensive and reliable, less subject to burn-out and vibration, and particularly it has the great asset of affording a direct mechanical linkage to a moving mechanism. Last, but not least, the actuator in its various forms of construction has, at a low cost, an amplification factor within one single unit that is sufficient to operate, from its output directly, the solenoids, relays and similar equipment that thus far needs multi-stage amplification and vulnerable electronic circuits of higher cost.

The actuator may be used as a centripetal governor, the opposite of a centrifugal governor. That is, if the speed of rotation is too high, the mercury is not permitted any longer to fall between the electrodes but is held to the wall by centrifugal power. This invention therefore provides for the important engineering application whereby actuation will occur only if the speed is below a maximum. If the speed of a motor or prime source of power falls below a safe minimum, only then is the mercury permitted to drop, thus actuating such auxiliary equipment as will restore the speed of the moving or rotating means to a safe number of revolutions per minute. For instance, an automatic gear shift would be actuated if the speed of the motor falls into the range where it would stall unless compensation is made by gear shift, gas input or other energy input, etc. to bring the basic speed of the motor back to a safe minimum wherein it is adequately operative.

The principle of construction illustrated in Figs. 9 and 9a may be used when dealing with a pendulous actuation. In this instance the mercury is released, say during clockwise motion. Then the pendulum swings back, the drop of mercury is lifted in counterclockwise motion and released again from a release point opposite the first one. Thus a pendulous motion may be amplified in the usual manner, keeping a pendulum in motion over electro-magnetic means of regeneration. Such a construction is of particular importance in the field of direct current electric clocks, be it low voltage such as used in battery operated clocks for cars or be they direct current clocks such as required in some direct current systems in some towns or cities.

In Fig. 8 there is disclosed a basic construction or arrangement for having a drop of mercury or other free conductive body operate a sequence of electrodes, and thus initiate sequences of operation of multiple circuits. This basic idea is shown applied in more practical form in Fig. 10. Therein in the end plugs 145, 146 may be insulating, for conductive current may or may not be taken off said end plugs. If more than two electrodes are provided to be energized, I may provide means extending through the insulated end plugs 145, 146 for establishing one pair of contacting electrodes 147, 148. Another pair of contacting electrodes 149, 150 are extended out through conductive paths to the mechanism that is connected to the actuating device. Contact to electrodes 149, 150 is then made as shown schematically through two ball bearings 151, 152, whereby current can be taken off through said two ball bearings independently of other contacting devices applied to the other pair of electrodes 147, 148. In this manner four electrodes can be operatively

employed, the active ends of which dip within the same vacuum container within which there is the drop of mercury or other free conductive body.

In Fig. 11 another construction is shown embodying changes in the actuating receptacle which make the same particularly positively active. The electrodes 153, 154 are thereby bent within the vacuum or gas filled receptacle or envelop in such manner as to hold the mercury drop mechanically between the ends of the receptacle and the tips of the respective electrodes. In this construction the receptacle or envelope 153a is desirably of glass, and, as shown in Fig. 11a, the receptacle is a short tube of small diameter, sealed at one end after being evacuated and filled with an inert gas, or it may remain a vacuum.

In Figs. 12 and 13 are shown other forms of actuating devices wherein the mercury or other free conductive body simply rolls under or in between two electrodes 155 and 156 or 157 and 158, the receptacles being indicated at 159 and 160, and being desirably of the same construction as in Fig. 11. In Fig. 12 the bead-covered electrodes are let in through thickened portions of the wall and then bent, and in Fig. 13 they are straight and short. The mercury is indicated at 160a in Figs 10 to 17.

In Figs. 14 and 15 the receptacle 161 is of elongated, tubular form with the opposite end portions bent in opposite directions in the general plane or path of rotation, as shown at 162, 163. The receptacle is rotated upon the axis 164 and the two electrodes enter through opposite walls 35 at the axis of rotation.

Fig. 16 shows a duplication or superposition of the construction shown in Figs. 14 and 15, whereby the mercury runs through the electrode only one single time within a 360° revolution. In other words, whereas the electrodes in Figs. 14 and 15 are arranged in such a manner that they are contacted by the drop of mercury each 180° of rotation, the construction shown in Fig. 16 presents to the mercury a bypass, so that only one of the two 180° of rotation drives the mercury between the electrodes while in the other 180° of rotation the mercury runs through a tube in which there are no electrodes. In Fig. 16 the two tube members are connected with each other at 50 opposite ends only.

Fig. 16 indicates a construction that is designed for the purpose of making one single actuation on a 360° rotation only. The mercury under these conditions passes through the two electrodes only once on a 360° revolution. This is important for such constructions where a single electrical impulse is to be established for 360° instead of the double count that the tubular construction shown in Figs. 14 and 15 provides for.

Fig. 16 shows a construction which incorporates a double twist into a toroid 165 rotating about an axis 166 at which the electrodes enter but only into one part or half of the toroid.

By this means a sudden release of the mercury is obtained which gives the important contacting and decontacting of the type shown in Figs. 14 and 15 with, however, the added feature that the mercury goes back to its original position over a different return path. Therefore, instead of pendulous motion from one side of the longitudinal tube or receptacle to the other, there is established a rotational motion whereby contacting is done on one side of the twist or toroid 75

while the other side, having no electrodes therein, acts as an inwardly bypass for the return of the mercury.

Fig. 17 shows a practical solution of the several problems hereinbefore discussed in that the electrodes 170, 171 are arranged in an axial line. However, the part of each electrode that is within the gas filled or vacuum receptacle or envelope 171a is bent at angles at 172, 173 so as to space the operative loops 174, 175 apart within the receptacle or envelope 171a. I, however, herein retain the mechanically important feature of positioning the electrodes 170, 171 co-axially. The construction shown in Fig. 17 has also the advantage that the part of each of the electrodes within the receptacle or envelope has a loop form. This forces the mercury to squeeze between the loop and the wall of the glass receptacle or envelope, thereby establishing more intimate contact between mercury and the electrodes.

Referring to all the forms of the actuator herein shown, in squeezing the mercury there is danger that it may break into small globules and thereby endanger the single impulse operation desired. To overcome this, the establishment of proper dimensions between the free path between the electrodes and the glass envelope is significant and has been known in the constructions shown. Moreover, to overcome the adhesion between mercury and glass on one side and mercury and electrodes on the other side, I desirably use powdered silica and in some instances lycopodium to keep the ball of mercury free moving and coherent. The size of the mercury globule, the inter-electrode distances, the glass tube size, and the gas pressure are significant to bring about reliable operation for different current carrying capacities of the switch, and are provided for by me in the construction shown. It also is important not to point one end of the glass tube in sealing off. This should be round. If pointed, a little remaining moisture or other imperfection makes the mercury stick within the pointed section. Therefore, rounded ends for immediate release are required, and also electrodes that hold the mercury bubble mechanically till it has sufficient gravitational pull to squeeze itself between the electrode and the wall, irreversibly passing between not one but both electrodes and establishing momentaneous contact.

In addition to the numerous uses of the actuator herein referred to by me, I state that the actuator in its numerous forms herein disclosed 55 may also be used with electric milkers, fire alarm systems, police call systems, flasher signals for call boxes or taxi service, marine signalling, as a control device for the starting of motors where certain circuits should be actuated only during the starting period and for a short moment. Also it is well adapted for the making of dots on recording apparatus, for operating turnstiles in subways, arenas, exhibitions, etc., for coin change mechanisms and coin rejector mechanisms.

The construction shown in Fig. 17 also has the added feature that the restriction established by the loops and the inner surface of the receptacle or envelope acts as a narrow throat, thereby holding the mercury in position until it is actually released as a whole unit, and then by necessity it must pass not only under the first electrode 174, but also under the second electrode 175, thus establishing positive actuation as well as decontacting.

Moreover, the construction shown in Fig. 17 also has the important feature that due to its constructural layout it is possible to position the electrodes significantly apart within the receptacle or envelope, as shown at 170, 175, while simultaneously retaining the good feature of the outside electrode leads being co-axially mounted. From a practical viewpoint a construction of this nature can be laid out to operate within substantial voltages, say up to 550 volts, or even higher. Many mercury switches suffer from the limitation that their construction requires a comparatively close proximity between the two contact points. By putting the electrodes into the vacuum receptacle or envelope over an angle, such as shown at 172, 173, it is possible then to separate the two electrodes within the receptacle or envelope, so that they are far enough apart from each other not to permit arcing.

The glass switch, such as shown in Figs. 11 to 17, while adequate from an electrical angle, needs packaging within a container, so as to make it of proper mechanical construction, to give it greater mechanical strength, facilitate its exchange, minimize rotary friction and improve electrical conduction through the rotary member.

If the leads 170 and 171, as shown in Fig. 17, were used not only to conduct the electrical current but also for mechanical support and contacting of the bearing, then difficulties would arise out of the position of the leads which may not necessarily always be exactly concentric though reasonably near so. Moreover the friction of a tungsten wire that has gone through methods of electronic tube production is considerable.

For the above electrical as well as mechanical engineering reasons, I do not use the leads as such as mechanical supports.

Instead I have provided special supporting fixtures. By these means the glass container with mercury and the leads protruding therefrom are freed from the duty of mechanical support, contacting and the establishment of rotary bearings which must be perfect both from an electrical and mechanical viewpoint. Any switch is no better than the connections from it. If the rotary contactor were not to give good electrical contact, there would occur failure of the circuit. Also, if the rotary friction in it were excessive, mechanical deficiency would be evident.

I have herein disclosed a rotatable switch that in certain forms at least is made of glass. In order to protect such a switch, I have, as shown at 179 in Fig. 18, done so by mounting it within a cylinder 180 of insulating material. This not only affords automatically to mount the inside rotating parts with ease in the outside fixture but also accomplishes this in such a manner that concentricity is achieved. This is desirable from the viewpoint of adequate performance despite simplicity of construction.

The electro-mechanical support, then, has to fulfill the following requirements:

(1) It has to relieve the glass tube and leads from mechanical strain. I achieve this by inserting the glass tube 179, Fig. 18, directly in an insulating holder or insulator cartridge 180a. This support has a transverse bore through which the tube is inserted essentially at a right angle to the rotary axis of the insulator. Since there are leads protruding from the glass tube, and also for the purpose of closing elastically around the tube, holding it firmly without breaking it, I have split

lengthwise the tube 180a. This facilitates insertion of the leads through the slots.

(2) In addition to the mechanical support, there is the problem of good electrical contacting with a minimum of friction. The basic solution to this is a metal to copper-carbon contact, the performance of which has been proven over many years in all motors that have brushes.

Fundamentally, two solutions of the problem are possible. The lead goes into a properly shaped carbon-copper part which part itself acts as a rotary support. This construction is shown in Fig. 18. One lead goes into a single part of good electrical conductivity and possesses a satisfactory degree of self-lubrication such as the graphite in a copper-carbon bearing. This bearing is shown as one single part at 177 and also at 178. To recapitulate, the glass tube is held mechanically in the insulator 180a. Inserted concentrically into the ends of the insulator are copper-graphite bearings. On one side the leads coming from the glass tube go into said bearing. On the other side, the copper-carbon cylinder is turned down in a lathe or otherwise properly shaped to a narrower diameter. This narrower rod rotates in the stator part of a mechanical bushing, such as 176, or it rotates in a counter-sunk hole of a conductive body such as the counterform in which 178 rotates.

In this manner there is provided the mechanical support of the graphite-copper solidly set into the insulating part 180a. Also there is the excellent electrical conductivity of the rotary part 177 rotating in its coform.

Fig. 18 discloses an electric-light bulb-flashing mechanism and one which constitutes a practical way to connect the sensitive rotary switch to whatever is to be controlled thereby, here shown as an electric-light bulb, but which may be any desired mechanical or electrical apparatus. The cylinder 180 is supported at its inner end by a bushing 182 pivotally mounted at 183 in an upright standard 184, whereby the switch 179 may be positioned at any angle with reference to the standard 184.

The bushing 182 is held in a split bearing that is tightened by a screw 184a when the cylinder 180 is set at the desired angle or inclination. The actual mechanical contact is herein made through the powder-metallurgy-formed copper-graphite bushing 176 rotating on polished pins or reduced portions of the bearings 177, 178, and in suitable bearings in the removable thick cylinder ends or heads.

A gear wheel or other suitable means of mechanical linkage may be applied in an insulated manner to said insulating cylinder 180 for rotating it and also rendering the device properly electrically insulated from the rest of the system.

The construction shown in Fig. 18 provides a mercury switch or actuator of greater current carrying capacity, it being mounted in an easily replaceable standard fixture. The current is taken off by circuit wiring through electrodes located concentrically within the strong cylinder 180 of insulating material. The pivot 183 provides for a compound angle which permits a longer time of passage between the conducting mercury and the contacting electrodes, according to the angle at which the cylinder 180 is tilted. The smaller the angle the slower the mercury will drop. By extending the angle beyond 90° it is possible to go through 0 and to start again. The electric-light bulb that is flashed is indicated at 185a. There is thus provided a con-

struction, shown in Fig. 18 and other figures, by which the receptacle or pulse switch has an open, interrupted circuit when the said receptacle is at rest.

The size of the bore in the closed receptacle 5 179 is such that the mercury, or free globule, must squeeze past the electrodes and not merely superficially contact them due to gravity. The mutual values of the total mass of the globule, its 10 surface tension, the bore of the insulating tube and the shape of the electrodes are all such as to insure that the mercury or other free globule does not touch the electrodes when the device is at rest. Such globule deforms under the mutual 15 influence of surface tension, the shape of the terminals, and the bore of the insulating tube, thereby providing that when the tube or closed receptacle rotates, intimate contacting is achieved when the free globule passes. The free globule 20 must pass, once it is past the release point. This is an irreversible action designed to produce one pulse, with the globule in interrupted, insulating condition when at rest.

Referring particularly to Fig. 18, the inner ends 25 of the terminals or electrodes are bent so as to produce better contacting with the free globule, and they are bent outside the tube or receptacle a second time, so that concentric connections are possible to the leads, even if the electrodes inside 30 must, by their very nature, be eccentric.

The second solution with respect to the electro-mechanical support (hereinbefore referred to) is basically as shown in Fig. 19. It is necessitated by such applications of my actuator, where the torque rotating the capsule, envelope or container 35 is so small that even the modest energy input required to move a copper-graphite cylinder within its co-form, as it is done in Fig. 18, would be excessive.

In such latter instance, where I must load 40 the driving member as little as possible, an instance which occurs with the wattmeter-driven actuators, I do not provide a long part of copper-graphite protruding into a bushing, but the opposite engineering solution is used. My invention therefore includes, as shown in Fig. 20a, the same copper-graphite bushing mentioned before. However, instead of turning it down to a smaller diameter which then forms the axial support, this bushing is drilled on both sides. 45 Into one side the lead 192 coming from the glass envelope is inserted. At the opposite side from said lead there is a hole. Into this hole fits a highly polished needle 194. This needle is held stationary in a metallic support 195, or, inversely, the needle may be held in the connective bushing so that it is connected electrically to the lead 192. If the latter is the case, the copper-graphite bushing would be on the outside, would 50 be stationary, and the needle would rotate in it.

The essence of the matter is that in one instance, where I deal with low friction, I use a polished needle rotating within a graphite bearing. In the other form of higher current-carrying capacity, though with somewhat higher rotational friction, the plugs inserted into the 55 end of the insulating tubing 180a form the electrical contact per se through their smaller-diameter shafts that protrude but are made of the same material and are integral with the plug, or a shaft (as, for example, of silver) may be inserted into the end.

In the construction shown in Figs. 19 and 20, the mercury switch or contacting device 186, of 70 any of the constructions herein shown, is elec-

trically linked to an electro-magnetic counter 187, thereby advancing said electro-magnetic counter two digits for every full rotation of the mercury switch or actuating mechanism.

In Fig. 19 is shown, in vertical longitudinal section, the said means for supporting the mercury switch or contacting device 186 that is itself represented in both Figs. 19 and 20 and, as stated, in Figs. 20a and 20b are shown alternative electrode supporting means.

In Fig. 19, in suitable upright plates 188, 189 secured to the insulator base 189 are bushings or points 190, 191 in which are supported the electrodes 191, 191. If desired, and as shown in Fig. 20a and as already referred to, the electrodes (one of which is represented at 192) may each extend into a copper-carbon brush 193 into which extends a polished needle 194 that is mounted in the insulated upright 195. Such construction provides for a minimum of friction and excellent electrical contact and is safe mechanically. Or if preferred, and as shown in Fig. 20b, each electrode 196 may be supported in a copper-carbon brush 197 that has an extension 198 supported in a suitable insulator 199. In both these constructions, as well as that shown in Fig. 19, the electrodes extend through suitable glass beads in the wall of the mercury switch or contacting device 186, as described with respect to constructions 30 already referred to.

In Fig. 20 is shown a slit 193a in the tubing. The walls of the said slit are held together by a collar 199b which in turn holds the gear wheel 186.

Referring to Fig. 19, it will be noted the insulating tube 193c is the only means for holding the upper part of the actuator in place between the two uprights 188, 189, which are spaced apart by the insulator base 189. In this construction, concentricity for the cup-and-needle units 190, 191 is difficult to achieve.

Referring again to Fig. 18, in order to achieve concentricity automatically, I use in addition to the inner insulator 188a the outer cylindrical tubing 180. By inserting into the tubing 180 the concentric ends 181, 181, I make sure that the conductive bushings 176, 176 are aligned concentrically, thus affording ease of rotation for the shafts 177 and 178.

In this manner I provide a packaged unit comparable, for instance, to the cylinder of a fuse that is concentric and that can be produced by inexpensive plastic molding and/or automatic screw machines, that is exchangeable if it ever should wear, and that can be removed and replaced by unskilled help.

Also, by using the construction shown in Fig. 18, I achieve a simple means of obtaining a compound angle for the drop of the mercury, by tilting the axis of the cylinder 180 with the aid of the swivel joint 183. The switch proper is important because it gives not only actuation but also de-actuation shortly after contacting has taken place. But the switch as such can be handled mechanically and electrically adequately only if mounted in the proper fixtures. Therefore the fixtures as disclosed are essential for making the glass-switches work.

Fig. 21 shows one of the many uses to which my invention may be put. Therein is shown a light buoy 209, the electric light 201 of which is controlled by any of the forms of my rotatable switch herein disclosed. I have therein shown at 202 a rotary switch that is similar to that shown in Figs. 17, 18 and 19. In said Fig. 21

a rheostat is shown at 203, an electric motor at 204, an electric coupling at 205 and batteries at 206.

The uses to which my invention may be put are exceedingly numerous. Without in any way limiting myself, I mention the following: watt meters; flash units for cameras (both still and slow-speed motion pictures); homing devices; gasoline metering; counter applications; nurse-call annunciator systems; railway signalling; flashing signals for street crossings; business machines; vending machines (coin changers, juke boxes); servo-mechanisms; demand meters; solenoid punch presses; positive counting machines for all types of mechanisms; solenoid operated printing devices; impulse generators for spark and other electrical equipment; lap counters for racing; calculating machines; speed governors; advertising signs, burglar alarm appliances; and electric fence actuators.

An important further use of my invention is to pick out a short time interval from a long time interval in various mechanisms. That is to say, unless cams are made unreasonably large, it is mechanically exceedingly difficult to have a very slow run, yet a fast release. It is difficult to gear a high-speed motor to a slow-speed mechanism. Such action can be made through a Geneva wheel but that is expensive. The herein disclosed mercury drop switch is much more positive. It is ideal for having, for instance, a synchronous timing motor driving the actuator and from it to operate a circuit every thirty seconds. If such a circuit is to be actuated for a few cycles only, the herein disclosed switch is preferably adapted thereto. If actuation should be for several seconds, a suitable time delay relay can be put in series.

Further advantages of my rotatable switch or actuator are the following. It can be operated practically within a minimum of friction. A cam operated device on the other hand has frictional losses. Another advantage of my herein disclosed switch or actuator is that it operates in a controlled atmosphere where freezing of points eventually occurs in switches operating in air. A further advantage of such switch or actuator is that although slight energy is required for its actuation, the interruption is complete. That is to say, in a miniature switch, for instance, which never operates completely reliably, the points separate at times only as little as $\frac{1}{16}$ ". Therefore, the controlling voltage is limited by the gap between the contact points and also the safety of operation. In my switch or receptacle or actuator, however, the drop of mercury being squeezed in the receptacle or envelope, and being squeezed also under the electrodes, offers a comparatively long bridge between the electrodes. If there is no mercury between them, they are separated by significant distance, possibly $\frac{1}{4}$ ". My switch or actuator therefore can be operated with a higher break-down voltage, say possibly 500 volts, where a micro-switch would spark, while complete extinction is possible with my switch or actuator which has the electrodes sufficiently far apart.

It is apparent from the foregoing description that the receptacle, container, envelope or capsule may be interposed in any circuit where it is desired to create an impulse of full current strength in order to operate a device of mechanical or electrical nature which requires a heavy current by means of a very small or weak current generating device, and hence devices requiring considerable power may be actuated or con-

trolled from sources of very small power. For example, a very small electric clock may be used to rotate the receptacle, and thus in turn to create impulses in the circuit of a large electric clock such as might be used in a church steeple. In like manner a very small impulse, such as generated in an electronic circuit, may be caused through the intermediary receptacle herein disclosed to control, actuate or follow a mechanism which consumes a large amount of power, by controlling the current flow in a conventional circuit within which the power consuming device is situated.

I may, if desired, coat or cover the mercury globule with a powder such as a silica powder, in order to control or prevent any adherence of the mercury to the interior of the receptacle, envelope or capsule, or to the electrodes, etc.

It should be understood that the present disclosure is for the purpose of illustration only and that this invention includes all modifications and equivalents which fall within the scope of the appended claims.

Having thus described a number of embodiments of the invention, it is to be understood that although specific terms are employed, they are used in a generic and descriptive sense, and not for purposes of limitation, the scope of the invention being set forth in the following claims.

I claim:

1. A circuit making-and-breaking device comprising a rotatable closed receptacle adapted to be interposed in an electric circuit and having therein spaced terminals, a free globule of conductive material in said receptacle that, upon each rotation of said receptacle, is thereby lifted bodily from an initially stable position therein to an unstable position, from which latter position it gravitates suddenly, to return to its said stable position, said spaced terminals being located in the return path of said free globule, which latter therefore makes contact with said terminals prior to the arrival of said free globule at its stable position, an insulator cartridge wherein said receptacle is mounted and which insulator cartridge is rotatable with said receptacle, and an outer supporting cylinder of insulating material, wherein the said insulator cartridge is itself mounted and wherein there are means to support the said outer supporting cylinder either in a horizontal plane or angularly with respect to a horizontal plane, whereby the speed of fall of the body of conductive material within the inner receptacle may be reduced if desired.

2. A circuit making-and-breaking device comprising a rotatable closed receptacle adapted to be interposed in an electric circuit and having therein spaced terminals, a free globule of conductive material in said receptacle that, upon each rotation of said receptacle, is thereby lifted bodily from an initially stable position therein to an unstable position, from which latter position it gravitates suddenly, to return to its said stable position, said spaced terminals being located in the return path of said free globule, which latter therefore makes contact with said terminals prior to the arrival of said free globule at its stable position, an insulator cartridge wherein said receptacle is mounted and which insulator cartridge is rotatable with said receptacle, and an outer supporting cylinder of insulating material, wherein the said insulator cartridge is itself mounted, and wherein the said insulator cartridge has copper-carbon brushes inserted into the ends thereof, said brushes having their outer

ends received in the ends of the outer supporting cylinder.

3. A circuit making-and-breaking device comprising a rotatable closed receptacle adapted to be interposed in an electric circuit and having therein spaced terminals, a free globule of conductive material in said receptacle that, upon each rotation of said receptacle, is thereby lifted bodily from an initially stable position therein to an unstable position, from which latter position it gravitates suddenly, to return to its said stable position, said spaced terminals being located in the return path of said free globule, which latter therefore makes contact with said terminals prior to the arrival of said free globule at its stable position, an insulator cartridge wherein said receptacle is mounted and which insulator cartridge is rotatable with said receptacle, the said receptacle being a cylinder the end walls whereof are spaced narrowly apart and which receptacle is of a diameter greatly exceeding its length and wherein the electrodes extend into the receptacle through its end walls at substantially the axis of rotation of said receptacle, the interior of the said receptacle being otherwise free of projections from the walls thereof, thereby permitting free movement of the said globule in said receptacle.

4. A circuit making-and-breaking device according to claim 1 wherein for mounting the insulator cartridge there are provided bearings 177 and 178 axially projecting at the ends thereof and centrally received in the end walls of the outer supporting cylinder.

5. A circuit making-and-breaking device according to claim 4 wherein one end wall of the outer supporting cylinder has an outwardly projecting bushing and wherein there is a standard in which said bushing is pivotally mounted for rotation.

6. A circuit making-and-breaking device according to claim 5 wherein there is provided on the standard a split bearing to receive said bushing.

7. A circuit making-and-breaking device according to claim 6 wherein means is provided to support said split bearing for up and down tilting movement, so that said receptacle and said cartridge may be held in a horizontal position or may be tilted upward or downward and be rotated in any of said positions.

8. A circuit making-and-breaking device according to claim 4 wherein the globule-containing cartridge is disposed intermediate the ends of the insulator cartridge with the respective axis of rotation in substantial coincidence.

9. A circuit making-and-breaking device according to claim 8 wherein the globule-containing cartridge has leads protruding endwise thereof and the insulator cartridge is split lengthwise to accommodate the leads and to facilitate firm holding engagement with the receptacle.

10. A circuit making-and-breaking device comprising a rotatable closed receptacle adapted to be interposed in an electric circuit and having therein spaced terminals, a free globule of conductive material in said receptacle that, upon each rotation of said receptacle, is thereby lifted bodily from an initially stable position therein to an unstable position, from which latter position it gravitates suddenly, to return to its said stable position, said spaced terminals being located in the return path of said free globule, which latter therefore makes contact with said terminals prior to the arrival of said free globule at its stable position, the said rotatable closed receptacle hav-

ing brushes 177 and 178, each having copper-carbon portions and by which the closed receptacle is supported simultaneously from both sides.

11. In a pulse switch, an insulating envelope containing a conductive liquid, electrodes spaced essentially symmetrically near the center of said envelope, said electrodes being bent so as to afford both a good contacting surface against the conductive liquid and serving simultaneously as a restraining element, whereby said conductive liquid must be deformed against the surface tension holding said liquid in an essentially globule-shaped condition within the cylindrical bore when said liquid does not contact the restraining and contacting electrodes, and giving a contact every substantially 180 degrees of rotation, one single pair of electrodes making possible contact operation essentially every 180 degrees, by reason of the switch being operative over a single path for the liquid both coming and going up and down respectively over said single path.

12. A pulse switch comprising an insulating envelope containing a mercury or like conductive globule, said switch having outer lead wires bent outside the envelope so that elongated parts of the lead wires go essentially through an axis of rotation of the insulating envelope, the direction of said axis being essentially subdividing and at a right angle to the single path along which the mercury or like globule moves, said pulse switch having electrodes 174 and 175 protruding from the outer connecting lead within the inside of the container, and being looped within said envelope so as to afford both electrical contacting and mechanical restraint of the conductive globule.

13. A pulse switch in accordance with claim 12, wherein there is provided means for holding the pulse switch in such a manner as to facilitate its operation and including copper-carbon brushes 177 and 178, both containing essentially coaxial holes for the envelope leads.

14. A pulse switch in accordance with claim 12, wherein means is provided for tilting the entire assembly so as to afford simplicity of establishment of a compound angle for varying the time of fall and the contacting of a conductive liquid connecting the inner, contacting electrodes.

15. A pulse switch in accordance with claim 12, that is of light construction and is provided with low-friction needle contacts holding the switch concentrically against rotation, the outer lead wires having bends providing for the lead wires extending coaxially, and needle holders therefor, the inner bends of said lead wires providing for the holding of the conductive liquid against surface tension and affording means for intimate electrical contacting while the conductive liquid squeezes past the same.

16. In a pulse switch in accordance with claim 12, a protective envelope holding concentrically means for providing contacts on both sides and substantially in the center of said pulse switch, the coaxial leads connecting concentric outer power leads, being part of the eccentrically bent inner electrodes.

17. A pulse switch in accordance with claim 12, wherein the lead wires are so shaped that their final outside wire, where contacting with an outer holding fixture, make suitable contact and essentially leave the pulse switch along a path constituting the axis of rotation of the pulse switch.

18. A pulse switch in accordance with claim 12, wherein the lead wires leave the sensing element in such a manner that the sensing element can rotate around them to operate the pulse switch,

the sensing element thereby rotating around the lead wires, essentially mounted to extend into the axis of rotation of the pulse switch.

19. A pulse switch in accordance with claim 12, wherein there is provided a non-conductive cartridge, wherein the pulse switch is mounted and wherein there are provided brushes inserted essentially into its axis of rotation.

20. A pulse switch in accordance with claim 12, wherein there are provided brushes in the axis of rotation of said switch and having substantially coaxial holes therein, and the lead wires protruding from the pulse switch and inwardly making electrical contact essentially coaxially, the lead wires being bent externally to fit said coaxial holes.

21. A pulse switch in accordance with claim 12, wherein there is provided a non-conductive cartridge that is split lengthwise so as to facilitate the insertion of the lead wires connected to the switch, there being provided two copper-carbon end-contacts mounted in the insulating envelope.

22. A pulse switch in accordance with claim 12, wherein there is provided an outer, second insulating, imperforate tube, the said second insulating tube surrounding the inner structure of the pulse switch so as to afford electrical insulation for the complete component and providing for simple exchange of the entire unit.

23. A pulse switch in accordance with claim 12, wherein there is provided an inside insulated holder having slits therein, and brushes at both ends thereof, and having holes toward the outside drilled into said brushes, and polished needles inserted into the outside of said brushes, thereby reducing to a minimum the frictional resistance against rotation and making possible the adequate rotary suspension of the member containing the pulse switch.

24. A pulse switch in accordance with claim 12, there being outer conductive supports 188, polished needles, brushes wherein said needles are mounted, thereby affording the rotation of the pulse switch with a minimum of friction.

25. A pulse switch in accordance with claim 12, there being outer conductive supports 188, pol-

ished needles, brushes wherein said needles are mounted, thereby affording the rotation of the pulse switch with a minimum of friction, the pulse switch having end-bushings wherein the said needles are mounted.

5 26. A pulse switch in accordance with claim 12, there being outer conductive supports 188, polished needles, brushes wherein said needles are mounted, thereby affording the rotation of the pulse switch with a minimum of friction, the pulse switch having end-bushings wherein the said needles are mounted, there being means for spacing the two outer conductors apart.

10 27. A pulse switch in accordance with claim 12, there being outer conductive supports 188, polished needles, brushes wherein said needles are mounted, thereby affording the rotation of the pulse switch with a minimum of friction, the pulse switch having end-bushings wherein the said needles are mounted, there being means for spacing the two outer conductors apart, there being an insulating mounting for the pulse switch with electrical conductors passing through both the ends thereof, and wherein there is means for rotating the pulse switch within said conductors.
